UNITED STATES PATENT OFFICE

GEORGE CAMPBELL, OF COHOES, NEW YORK.

IMPROVEMENT IN THE MEANS FOR ADJUSTING KNITTING-BURRS.

Specification forming part of Letters Patent No. **152,968**, dated July 14, 1874; application filed June 20, 1874.

To all whom it may concern:

Be it known that I, GEORGE CAMPBELL, of Cohoes, in the county of Albany and State of New York, have invented a new and useful Improvement in Knitting-Machines, of which the following is a specification:

My invention consists of the arm which supports the rotating loop, or stitch adjusting or discharging burr, of a knitting-machine, fitted on a vertical screw-stud of the permanent arm, and having a thumb-nut below and a jam-nut above, together with a steady-pin in one of the arms working freely through the other, whereby the vertical adjustment of the burr relatively to the needles, and to the other burrs, can be easily and accurately effected, and the arms be rigidly and permanently fastened.

Figure 1 is a sectional elevation of my improved adjusting apparatus, and Fig. 2 is a horizontal section taken on line *xx* of Fig. 1.

Similar letters of reference indicate corresponding parts.

A is the permanent arm; B, the adjustable arm carrying the burr C. D is the screw-stud rising from the permanent arm through the arm B, which has a boss, F, through which the hole for the screw is made, and also a re-

cess, G, in the under side for the reception of the adjusting-nut H on the screw-stud, the boss being to hold the arm so that it shall not wabble on the screw, and the recess being to allow the arm B to drop down on the supporting-arm A. J is a binding-nut on the stud above the boss F, to bind the arm B fast after being adjusted by the nut H. K is the steady-pin to prevent the arm B from turning around on the screw-stud.

In this example the steady-pin is fixed in arm B, and works in the arm A, but in practice I will have the pin fixed in arm A, and working in arm B. The milled edge of the nut H projects beyond the edges of the arm B sufficiently to be worked readily.

Having thus described my invention, I claim, as new and desire to secure by Letters Patent—

The adjustable burr-supporting arm B of a knitting-machine, connected to the stationary arm by the stud-screw D, adjusting-nut H, binding-nut J, and steady-pin K, for adjusting and securing it in the manner described.

GEORGE CAMPBELL.
